UNITED STATES PATENT OFFICE

164,422

WATER FAUCET AERATOR

Orloff W. Holden, Chicago, Ill., assignor to Orloff W. Holden and Marguerite H. Holden, a partnership doing business as Knickerbocker Rubber Company, Not Inc., Chicago, Ill.

Application April 19, 1950, Serial No. 9,319

Term of patent 14 years

(Cl. D91—3)

To all whom it may concern:

Be it known that I, Orloff W. Holden, residing in the city of Chicago, county of Cook, State of Illinois, have invented a new, original, and ornamental Design for a Water Faucet Aerator, of which the following is a specification, reference being had to the accompanying drawing, forming a part thereof, in which:

Fig. 1 is an elevational view of a water faucet aerator showing my new design;

Fig. 2 is a top plan view thereof; and

Fig. 3 is a bottom plan view thereof.

I claim:

The ornamental design for a water faucet aerator, substantially as shown.

ORLOFF W. HOLDEN.
